233,519

BUILDING

Paul Ear Chen, Glen Ellyn, and Joseph Charles Manganello, Naperville, Ill., and Gordon Elliott Sylvester, Jamaica, N.Y., assignors to Bell Telephone Laboratories, Incorporated, Murray Hill, N.J.

Filed Mar. 9, 1973, Ser. No. 339,561

Term of patent 14 years

Int. Cl. D25—03

U.S. Cl. D13—1 R

FIG. 2

FIG. 3

FIG. 1 is a perspective view of the front and left side of a building embodying our new design;

FIG. 2 is a front elevation of the building shown in FIG. 1;

FIG. 3 is a rear elevation of the building shown in FIG. 1;

FIG. 4 is a left side elevation of the building shown in FIG. 1; and

FIG. 5 is a right side elevation of the building shown in FIG. 1.

We claim:

The ornamental design for a building, substantially as shown and described.
